UNITED STATES PATENT OFFICE.

JOHN GRIFFIN, OF LOUISVILLE, KENTUCKY.

IMPROVEMENT FOR CHANGING THE SPEED OF STEAM-CARRIAGES.

Specification forming part of Letters Patent No. **31,455**, dated February 19, 1861.

To all whom it may concern:

Be it known that I, JOHN GRIFFIN, of Louisville, in the county of Jefferson and State of Kentucky, have invented a new and Improved Steam Cotton Picker or Harvester; and I do hereby declare that the following is a full, clear, and exact description of the same, reference being had to the annexed drawings, making a part of this specification, in which—

Figure 1 is a side sectional view of my invention; Fig. 2, a transverse vertical section of the same taken, in the line $x x'$, Fig. 1.

Similar letters of reference indicate corresponding parts in the two figures.

The object of this invention is to obtain a ready means whereby the steam-carriage which contains the cotton-receivers and also the exhaust-chambers, together with the means for exhausting the same, may be driven at a fast or slow speed, as occasion may require, a fast speed being required when the steam-carriage is being driven from place to place, and a comparatively slow speed required when the device is at work.

To enable those skilled in the art to fully understand and construct my invention, I will proceed to describe it.

A represents a platform, which contains a rectangular framing B and is supported by two pairs of wheels C D, the axle a of the back wheels being attached by a king-bolt to a bolster c at the back part of the platform, so as to admit of the ready turning of the machine. The front wheels D are fitted on independent axles $d d'$, as shown clearly in Fig. 2, the driving-power being applied to the axle d' .

On the platform A there is placed a steam-engine E. The cylinder e of the engine is provided with trunnions f and is hung in bearings g , precisely the same as an oscillating engine. The piston-rod h of the cylinder e is connected by a pitman i with a crank j , which is on a vertical shaft k . The lower end of shaft k has a pinion l on it, and this pinion gears into a wheel m on the axle d' , as shown plainly in both figures. The wheel m is allowed to slide on the axle d' , so that the wheel

may be shoved in and out of gear with pinion l , as may be desired.

To the piston-rod h there is attached a frame F, which is composed of four horizontal rods i' , attached at their ends to plates $j' j'$. The rods i' pass through upright plates $k' k'$, attached to the platform A, said plates serving as guides for the rods.

To the end of the frame F—the end opposite to that where the piston-rod h is attached—there is secured the piston-rod l' of an air-pump G, which exhausts receivers H H on the framing B. The engine E therefore, it will be seen, operates the pump G through the medium of the frame F, and at the same time propels the carriage along through the medium of the crank j and gearing $l m$, and this gearing will propel the carriage along at a very moderate speed, owing to the relative size of the wheels $l m$.

The axle d' is provided with a crank n , to which a pitman H' is attached, as shown clearly in Fig. 1.

When it is required to drive the carriage with a quick speed, the piston-rod h is detached from the frame F and attached directly to the pitman H' . In this case the cylinder e operates as an oscillator and a quick movement is given the carriage.

The cylinder e is shown attached to the pitman H' in red outline in Fig. 1.

When the engine E is used as an oscillator, the wheel m is shoved out of gear with pinion l .

Having thus described my invention, what I claim as new, and desire to secure by Letters Patent, is—

The arrangement, essentially as shown, of the steam-cylinder e , hung on trunnions f , in connection with the reciprocating frame F, air-pump G, pitmen $H' i'$, and gearing $l m$, whereby the speed of the carriage may be changed from fast to slow, and vice versa, as occasion may require.

JOHN GRIFFIN.
